CLAIM

The ornamental design for an automobile gas cap tool, as shown and described.

DESCRIPTION

FIG. 1 is a front elevational view of an automobile gas cap tool showing our new design, the rear elevational view being identical;

FIG. 2 is a right side elevational view thereof, the left side elevational view being identical;

FIG. 3 is a top plan view thereof;

FIG. 4 is a bottom plan view thereof;

FIG. 5 is a perspective view thereof, the gas cap shown in broken lines is for environmental purposes only and forms no part of the claimed design; and,

FIG. 6 is a perspective view thereof, shown in use with the broken lines to indicate environment only and to form no part of the claimed design.
